APPARATUS FOR EVAPORATION

Philip B. Sadtler, South Norwalk, Conn., assignor
of one-half to Henry M. Hunter, Brooklyn,
N. Y., and one-half to George D. Dickey, Ridge-
wood, N. J.

Application August 25, 1948, Serial No. 46,147

5 Claims. (Cl. 159—17)

1

This invention relates to multiple effect evaporation and more particularly to a novel method and apparatus for heating evaporating liquors either prior to their introduction into the evaporator or during their transfer from one effect to another effect of the evaporator.

In the operation of a multiple effect evaporator, it is desirable that the liquor introduced into each effect be at or close to its boiling point to increase the amount of the evaporation that occurs within the effect. In cases where the flow of liquor and vapor in the evaporator is concurrent, this objective is automatically achieved since the liquor entering a particular effect comes from a preceding effect that is operating at a higher temperature, and hence the liquor entering the particular effect is normally at or above its boiling point for the conditions existing in that effect. On the other hand in cases where the flow of liquor is countercurrent to the vapor flow, the liquor transferred from one effect to another must be heated up as it is transferred if it is to enter the succeeding effect at its boiling point under the conditions existing in the succeeding effect.

There are certain points in a multiple effect evaporator at which vapors are produced in an amount that is in excess of that required for maintenance of balanced conditions within the evaporator, and these vapors are available for use in preheating the liquors where preheating is desirable. To the extent that such excess vapors are used for liquor preheating, the overall economy of the evaporator is improved.

It is accordingly an object of the present invention to provide a novel method and apparatus whereby such excess vapors may be utilized to preheat the liquors to their boiling points. It is another object of the invention to effect such preheating of the vapors with a minimum amount of heat transfer area. It is still another object of the invention to provide unusually compact and relatively inexpensive apparatus for effecting such preheating of the liquor. Other objects of the invention will be in part obvious and in part pointed out hereafter.

The many objects and advantages of the present invention may be best understood and appreciated by reference to the accompanying drawings which illustrate apparatus incorporating a preferred embodiment of the present invention and wherein:

Figure 1 is a flow sheet showing diagrammatically a quintuple effect evaporator incorporating the present invention;

2

Figure 2 is a side view of one of the heating elements of the evaporator shown in Figure 1 with the end portions of the heating element shown in vertical section;

5 Figure 3 is a vertical section through one end portion of the heating element taken on the line 3—3 of Figure 2, and showing the partitions that define the preheating section of the heating element;

10 Figure 4 is a vertical section through the other end of the heating element taken on the line 4—4 of Figure 2 and further showing the partitioning of the heating element;

15 Figure 5 is a perspective view of one end of the heating element broken away to show still further details of the partitioning;

20 Figure 6 is a vertical section through a modified form of the structure of Figure 2 wherein the heating element is located within an evaporator body;

25 Figure 7 is a fragmentary horizontal section taken on the line 7—7 of Figure 6 and showing a partition that isolates a preheating section of the heating element of Figure 7, and

30 Figure 8 is a fragmentary horizontal section taken on the line 8—8 of Figure 6 and further showing partitions that isolate the preheating section.

Referring to the drawings and more particularly to Figure 1, the quintuple effect evaporator there shown comprises a dual first effect having the evaporator bodies 10a and 10b and four subsequent effects having the evaporator bodies, 12, 14, 16 and 18 respectively. The evaporator

35 bodies are connected by pipes 20a, 20b, 22, 24, 26 and 28 respectively, to the pumps 30a, 30b, 32, 34, 36 and 38 respectively. Liquor contained in each evaporator body is withdrawn by its associated pump and pumped through pipes 40a,

40 40b, 42, 44, 46 and 48 respectively, to the tube side of tube-in-shell heating elements 50a, 50b, 52, 54, 56, and 58 respectively, and then returned to the evaporator bodies through the pipes 60a,

45 60b, 62, 64, 66 and 68 respectively. Thus liquor contained in each evaporator body is circulated through an external heater and then returned to the evaporator body wherein the vapor is separated from the liquor and caused to flow on to a subsequent effect.

50 Steam to heat the first effect is supplied through a pipe 70 and flows through the branch pipes 70a and 70b to the shell sides of heating elements 50a and 50b respectively. Vapors evolved in the bodies 10a and 10b of the first effect pass through the branch pipes 72a and

725 respectively, thence through pipe 72 to the heating element 52 of the second effect. In like manner vapors from the bodies 12, 14 and 16 pass through the pipes 74, 76 and 78 respectively, to the heating elements 54, 56 and 58 respectively of the third, fourth and fifth effects. Vapors evolved in the fifth effect pass through the pipe 80 to a condenser 82 wherein they are condensed.

Steam condensate from the heaters 50a and 50b is withdrawn through the pipes 84a and 84b respectively, and conducted to a suitable point of disposal. Condensate from the heating elements 52, 54 and 56 is conducted by pipes 86, 88 and 90 respectively, to the shell sides of heating elements 54, 56 and 58 respectively, to take advantage of such flash evaporation as may occur at the successively lower pressures existing within successive heating elements. Condensate from heating element 58 is withdrawn through pipe 92 and pumped by a pump 94 to a suitable point of disposal.

The liquor to be evaporated is fed to the third effect of the evaporator and more particularly is introduced into the pipe 24 from a feed pipe 96. Liquor is transferred from the evaporator body 14 to the body 16 through a pipe 98, and from the body 16 to the body 18 through a pipe 100. Since the evaporator bodies 14, 16 and 18 operate at successively lower pressures, no pump is required to effect these transfers.

The liquor from the fifth effect of the evaporator is transferred to the second effect, and in accordance with the present invention this liquor is preheated before being introduced into the second effect by being passed through the same heating elements in which it was previously heated for purposes of vaporization. The internal structure of the heating elements that permits the preheating and vaporizing steps to be carried out simultaneously in the same apparatus is described more fully hereafter.

Liquor is withdrawn from evaporator body 18 through a pipe 102 and pumped by pump 104 through pipe 106 to the heater 58 wherein it is partially preheated. From heater 58 this transfer liquor passes successively through pipe 108, heating element 56, pipe 109, heating element 54 and pipe 110 to the pipe 22 of the circulating system of the second effect.

Liquor is transferred from evaporator body 12 to body 10b through pipe 112, pump 114 and pipe 116, and from body 10b to body 10a through pipe 118, pump 120 and pipe 122. The concentrated liquor from body 10a flows through pipe 124 to a flash chamber 126 wherein flash evaporation occurs. Vapors from the flash chamber 126, which comprise the excess vapors previously referred to, are available for preheating the liquor and are conducted by pipe 128 to the vapor pipe 74 through which they flow to the heating element 54. The concentrated liquor is withdrawn from chamber 126 through pipe 130 and pumped by pump 132 to a suitable point of disposal.

The preheating in the heating elements 58, 56 and 54 of the liquor transferred from body 18 of the fifth effect to body 12 of the second effect is an important feature of the present invention. The arrangement is such that excess heat available in the vapors supplied to these heating elements is utilized to raise the temperature of the liquor substantially to its boiling point and thus the thermal efficiency of the evaporator is materially increased. Also since the preheating is carried out in the same heat-

ing element that supplies heat for vaporization, the heating surface of the heating element is more efficiently used and hence a smaller heat transfer area can be used for a given evaporator capacity. Moreover, the equipment cost is substantially less than it would be if, for example, separate heating elements were provided.

The heating elements 54, 56 and 58 may be similarly constructed and the construction of one of these elements is shown in Figures 2-5 of the drawing. Referring to Figures 2-5, the heating element there shown comprises a cylindrical casing 140 in which the spaced tube sheets 142 and 144 are mounted and support the tubes of a tube bundle 146 in the usual manner. The casing 140 has the usual vapor connection 141 and condensate connection 143. At its opposite ends the heating element is provided with the heads 148 and 150 that enclose the ends of tubes 146.

As previously indicated the heating element has formed therein partitions that effectively divide the tube bundle 146 into a vaporizing section and a preheating section. Referring particularly to Figures 3 and 5, within the head 148 there is a partition 156 that extends from the outer end of the head to the tube sheet 142 and effectively isolates a relatively small segment of the tube bundle 146 as a preheating section. The remainder of the tube bundle, comprising a major fraction of the tubes, constitutes the vaporizing section of the heating element and communicates with a chamber 151 defined by head 148, tube sheet 142 and partition 156.

As shown in Figure 5 the partition 156 is mounted at its inner end in a channel-shaped member 158 that is preferably made of a resilient material, such as rubber, to provide an adequate seal and prevent liquid communication between the preheating section and the vaporizing section of the tube bundle. The preheating section is internally divided by the partitions 152 and 154 that extend from the partition 156 to the side wall of head 148 and define three chambers 164, 165 and 166 communicating with separate banks of tubes of the preheating section. The chamber 166 is provided with an inlet connection 160 and the chamber 164 is provided with a discharge connection 162.

Referring to Figure 4 the head 150 at the opposite end of the heating element is provided with a partition 168 that is similar to the partition 156 and with a second partition 169 that extends horizontally across the diameter of the heating element. The partitions 168 and 169 divide the space within head 150 into an upper chamber 170 and lower chamber 171 communicating with the vaporizing section of the heating element and into an upper chamber 172 and lower chamber 173 communicating with the preheating section of the heating element. The chamber 171 is provided with an inlet connection 174 and the chamber 170 is provided with a discharge connection 175.

The construction is such that the preheated liquor makes four passes through the tube bundle, whereas the liquor to be vaporized makes only two passes through the tube bundle. The liquor to be vaporized enters the chamber 171 through inlet 174 and because of the partition or baffle 169 is directed through the tubes of the lower portion of the vaporizing section to the chamber 151 at the opposite end of the heating element. This liquor then returns through the tubes of the upper portion of the vaporizing section to

the chamber 170 and leaves the heating element through connection 175.

The liquor to be preheated enters the chamber 166 through connection 160 and is directed by partition or baffle 154 into the lowermost group of tubes of the preheating section through which it flows to the chamber 173. From chamber 173 the liquor flows back through a second bank of tubes to chamber 165, thence through a third bank of tubes to chamber 172, and a fourth bank of tubes to chamber 164, whence it leaves the heating element through discharge connection 162.

The method and apparatus of the present invention may also be used in evaporators of the type wherein the heating element is mounted within the evaporator body, and a structure of this sort is shown in Figures 6-8 of the drawings. Referring to these figures, the numeral 180 designates the casing of an evaporator body within which is mounted in the usual manner a pair of spaced tube sheets 182 and 184 supporting the tubes of a tube bundle 186. The lower ends of tubes 186 are enclosed by a head 188 that cooperates with the tube sheet 184 to define a space which is divided by the partitions 190 and 192 into three chambers 194, 196 and 198.

At the top of the tube bundle 186 a cap or head 200 cooperates with the tube sheet 182 to define a chamber 202 in such manner as to isolate a segment of the tubes of the tube bundle 186 from the remainder of the tubes. The head 200 is held against the tube sheet 182 by a support 204 that is fixed to the casing 180 of the evaporator body. A conventional curved baffle 206 is mounted in the usual manner above the upper ends of tube 186. The partitions 190 and 192 and the head 200 serve to divide the tube bundle into a preheating section and a vaporizing section.

The liquor to be evaporated enters the chamber 194 through an inlet connection 208 and flows upwardly through the tubes of the vaporizing section of the tube bundle 186. Steam is supplied to the outer surfaces of tubes 186 through a steam inlet connection 210 and condensate is removed through a condensate discharge connection 212. The liquor from chamber 194 is heated and partially vaporized within the tubes as it flows upwardly therethrough. Upon leaving the tubes the vapor and liquor are separated and the vapor passes into the upper portion of the evaporator body, whereas the liquor is withdrawn through a discharge connection 214. The baffle 206 assists in preventing entrainment of liquor with the vapors.

The liquor to be preheated enters chamber 196 through an inlet connection 216 and flows upwardly through the bank of tubes that communicates with chamber 196. At the top of the tube bundle the preheated liquor flows through chamber 202 and downwardly through a second bank of tubes to chamber 198, whence it is withdrawn through a discharge connection 218. Thus with the construction shown, separate portions of liquor may be vaporized and preheated in the single heating element of the evaporator body.

From the above description it should be apparent that the present invention provides a novel method and apparatus for achieving the objects set forth above. Excess heating vapors available within the evaporator are utilized to preheat the liquor, and the preheating is carried out in the same preheating element in which the main bodies of liquor are vaporized. By carry-

ing out both heating steps in the same piece of equipment, unusually effective utilization of heat transfer area is achieved and substantial economies in the cost of equipment are effected.

5 Since many embodiments might be made of the present invention and since many changes might be made in the embodiment disclosed herein, it is to be understood that the foregoing description is to be interpreted as illustrative only 10 and not in a limiting sense.

I claim:

1. An evaporator effect adapted to be incorporated in a multiple-effect evaporator comprising in combination, an evaporator body, a tube-in-shell heating element, the end portions of said heating element being provided with partitions to divide said heating element effectively into a vaporizing section and a preheating section to provide for simultaneously preheating and vaporizing distinct bodies of liquor within said heating element, a first and second conduit interconnecting spaced points near the bottom of said evaporator body with spaced points in the vaporizing section of said heating element to establish a closed circulating system including said evaporator body and said vaporizing section, a pump located in said circulating system for circulating liquor therethrough, a third conduit interconnecting a third spaced point near the bottom of said evaporator body and the preheating section of said heating element, and a pump located in said third conduit for withdrawing liquor from said evaporator body and pumping it to and through said preheating section of said heating element.

2. A multiple effect evaporator of the mixed flow type, comprising in combination, a first group of effects connected for countercurrent flow of liquor and vapor, a second group of ef-

40 fects connected for concurrent flow of liquor and vapor, each of said effects including an evaporator body, a heat exchanger and a pump connected to circulate liquor from said evaporator body through said heat exchanger back to said evaporator body, at least one of said heat exchangers of said second group of effects being provided with internal partition means dividing said exchanger into a main heating zone wherein said circulating liquor is heated and a preheat- 45 ing zone, and a liquor conduit interconnecting an effect of said second group with an effect of said first group, said conduit including the preheating zone of said one heat exchanger whereby liquor flowing through said conduit from said sec- 50 ond group of effects is preheated before reaching said first group of effects.

3. A multiple effect evaporator of the mixed flow type, comprising in combination, a first group of effects connected for countercurrent flow of liquor and vapor, a second group of effects connected for concurrent flow of liquor and vapor, each of said effects including an evaporator body, a heat exchanger and a pump connected to circulate liquor from said evaporator body through said heat exchanger back to said evaporator body, each of said heat exchangers of said second group of effects being provided with internal partition means dividing said exchanger into a main heating zone wherein said circulating liquor is heated and a preheating zone, and a liquor conduit interconnecting an effect of said second group with an effect of said first group, said conduit including the preheating zone of each of said heat exchangers whereby liquor flowing through said conduit from said second group

of effects is preheated before reaching said first group of effects.

4. A multiple effect evaporator of the mixed flow type, comprising in combination, a first group of effects connected for countercurrent flow of liquor and vapor, a second group of effects connected for concurrent flow of liquor and vapor, each of said effects including an evaporator body, a heat exchanger and a pump connected to circulate liquor from said evaporator body through said heat exchanger back to said evaporator body, each of said heat exchangers of said second group of effects being provided with internal partition means dividing said exchanger into a main heating zone wherein said circulating liquor is heated and a preheating zone, and a liquor conduit interconnecting the last effect of said second group with the last effect of said first group and including a liquor transfer pump and the preheating zone of each of said internally divided heat exchangers whereby liquor from the last effect of said second group is preheated before passing through the last effect of said first group.

5. A multiple effect evaporator of the mixed flow type, comprising in combination, a first group of effects connected for countercurrent flow of liquor and vapor, a second group of effects connected for concurrent flow of liquor and vapor, each of said effects including an evaporator body, a heat exchanger and a pump connected to circulate liquor from said evaporator body through said heat exchanger back to said evaporator body, each of said heat exchangers of said second group

of effects being provided with internal partition means dividing said exchanger into a main heating zone wherein said circulating liquor is heated and a preheating zone, and a liquor conduit interconnecting the last effect of said second group with the last effect of said first group, said conduit including a liquor transfer pump and the preheating zone of each of said heat exchangers, said preheating zones being connected into said conduit in series relation, whereby liquor leaving the last effect of said second group of effects flows first through the preheating zone of the heat exchanger of said last effect and then successively through the preheating zones of the heat exchangers of successive preceding effects of said second group before passing to the last effect of said first group of effects.

PHILIP B. SADTLER.
